US00D847634S

(12) **United States Design Patent** (10) Patent No.: **US D847,634 S**
(45) Date of Patent: ** May 7, 2019

(54) **HOLDER FOR PACKING CONTAINER**

(71) Applicant: **Kao Corporation**, Tokyo (JP)

(72) Inventor: **Maki Hatakeyama**, Tokyo (JP)

(73) Assignee: **Kao Corporation**, Tokyo (JP)

(**) Term: **15 Years**

(21) Appl. No.: **29/635,323**

(22) Filed: **Jan. 30, 2018**

(51) LOC (11) Cl. **09-07**

(52) U.S. Cl.

USPC **D9/455**

(57) **CLAIM**

The ornamental design for a holder for packing container, as shown and described.

DESCRIPTION

FIG. 1 is a front perspective view of a holder for packing container showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a bottom perspective view thereof.

1 Claim, 5 Drawing Sheets
